UNITED STATES PATENT OFFICE.

HERBERT A. WOOFTER, OF KENTON, OHIO, ASSIGNOR TO SWIFT ELECTRIC WELDER COMPANY, OF DETROIT, MICHIGAN, A CORPORATION OF MICHIGAN.

SWITCH.

Application filed May 24, 1926. Serial No. 111,402.

This invention relates to switches and more particularly to an improved construction of regulator switch.

The invention finds particular utility in connection with those types of switches which, either because of their use in high tensioned circuits, or for other reasons, are provided with a plurality of contact elements, the surfaces of each of which are of a relatively large area. In the conventional forms of regulator switches it is customary to arrange these contacts in a row in spaced relation whereby they may be selectively or successively engaged by a movable contact element or arm. In the character of switches aforementioned where contacts of relatively large area are provided it is furthermore customary to form the movable contact element or arm with a contact surface of substantially the same area as that of each contact. However, in constructing the switches of this character heretofore manufactured, it was necessary to space the contacts from one another a distance greater than the width of the movable contact element or arm so that during the successive engagement of this arm with the contacts, a complete disengagement between the contact arm and one contact would be accomplished before the movable arm engaged the next succeeding contact to thereby eliminate the possibility of bridging the stationary contacts and causing a short circuit. Consequently in regulating switches employing a plurality of contacts, the necessary wide spacing of the contacts either increased the total size of the switch beyond reasonable limits, or placed a limitation upon the number of contacts which might be provided. While the difficulties above mentioned were experienced more appreciably in connection with switches requiring, for the purposes of efficiency, relatively large contact surfaces, nevertheless the same conditions present themselves in smaller and more compact switches of the regulator type involving a series of spaced contacts and movable contact elements associated therewith.

It is therefore one of the primary objects of this invention to provide a switch wherein the aforementioned problems and difficulties are solved and overcome by providing means for causing a relative transient separation of the contact arm and contacts in a substantially relative perpendicular direc-

tion during the movement of the contact arm from one contact to another. By such a construction it is possible to arrange the contacts spaced apart a distance less than the width of the movable contact arm without liability of a bridging of the contacts and consequential short circuiting during the operation of the switch.

Many other objects, advantages and novel details of construction are involved in the present invention, all of which will be made more apparent as this description proceeds, especially when considered in connection with the accompanying drawings wherein,

Figure 1 is a front elevational view, with certain parts broken away, of a switch constructed in accordance with this invention.

Figure 2 is a central vertical sectional view through the switch.

Figure 3 is a fragmentary detail sectional view taken substantially on the plane indicated by the line 3—3 of Figure 1.

Figure 4 is a fragmentary detail sectional view taken substantially on the plane indicated by the line 4—4 of Figure 1.

Figure 5 is a fragmentary view taken substantially on the plane indicated by line 5—5 of Figure 2.

Referring now particularly to the drawings wherein like reference characters indicate like parts, it will be noted that the reference character 10 indicates a switch board or base constructed as customary of insulating material to the front face of which a plurality of spacer sleeves 11 are secured for mounting a front panel 12 in spaced relation to the board 10. Bolts or the like 13 pass through front panel 12, the sleeves or bushings 11 and through the board 10 uniting and holding these parts in the relation illustrated in Figure 2 of the drawings. The cover 14 is arranged peripherally of the switch for enclosing and protecting the operative parts thereof and extends, in the embodiment herein illustrated, around three sides thereof, the ends of this cover being anchored at 15 to two of the bushings 11.

Mounted upon the board 10 is a plurality of contact plate studs 16, each of which is provided with a threaded rearwardly projecting extension 17 for engagement with terminals 18 of the electrical leads (not shown) connecting the switch to the transformer or other device to be controlled. These terminals may be conveniently secured

in place by means of nuts 19. Each contact plate stud 16 has a forwardly directed stud-like extension 20 which passes through the board 10 and has a threaded engagement with the contact plate 21. In the embodiment of the invention herein shown, two of the elements 16 are associated with each contact plate 21 and after the threaded engagement therebetween has been effected as 5 10 15 20 25 30 lever. During the movement of the contact arm from one contact to the next succeeding one, the surface 44 of the arm 42 engages a cam surface on the cam ring 45 and is accordingly rocked about its shaft 43 in a direction which moves its upper end thereof substantially perpendicularly with respect to the contact surface 24. The shape and extent of the cam surface is such that the end of this lever is held thus out of the plane of its contact until the contact lever 27 has cleared the previous contact and is adjacent the next succeeding one whereupon the arm 42 is permitted to again move into engagement with the contact surface 24 of the next contact. Hence during the transient movement of the contact arm 27 from one contact to the next the contacting ends of the elements 27-42 are moved apart or in substantially opposed directions to clear the contacts and do not again come into contacting relation until they are in substantial alignment or superposed relation with the next succeeding contact. Thus liability of 25 bridging a pair of contacts 21 is eliminated notwithstanding the fact that the contact arm is wider than the distance between the contacts 21.

As mentioned, the lead from the source of current is connected to the terminals 35 and is conducted through the jumper 34 to the contact arm 27. The current passes through this arm to the selected contact 21 thence through the windings of the transformer 35 connected to the selected contact and then back through leads (not shown) to the source of current. For convenience the return lead may be connected to terminals 51 mounted upon the board 10, the current 40 passing through studs 52 and out through terminal connections 53 to which the return lines to the source of current are connected. Such a connection is unnecessary but in practice is convenient as the leads to and 45 from the source of current are usually protected by conduits which extend to a point adjacent the switch board and the structure herein described provides means for conveniently connecting both the incoming and return lines.

A switch constructed as above described has been found to give remarkably good results in practice but it is evident from the above considerations that the specific design 55 hereinbefore described is only typical of the various forms in which the invention may be embodied and accordingly reservation is made to make such changes as may come within the purview of the accompanying claims.

What I claim as my invention is:

1. In a regulator switch, a contact arm and a pair of contacts spaced apart a distance less than the width of said contact 65 arm and means including a plurality of

rollers engageable with said arm for moving the same substantially perpendicularly to its plane of contact during its transient movement between contacts.

2. In a switch, a pair of contacts, a movable contact arm having spaced members engageable therewith and cam means independent of said contacts operable upon a movement of said arm for oppositely moving the said members out of their planes of contact.

3. In a regulator switch, a pair of contacts, a movable contact arm having spaced members engageable with said contacts and means engaging said arm and one of said members during their transient movement between contacts for simultaneously moving said members out of their planes of contact.

4. In a regulator switch, a pair of contacts, a resilient contact arm having portions adapted for successive clamping engagement with said contacts and means between said contacts for releasing said clamping portions during transient movement of said arm between contacts.

5. In a switch, a pair of contacts, each provided with opposed contact surfaces, a contact arm having parts concurrently engageable with said opposed surfaces and means for moving said arm parts out of their plane of contact upon the transient movement of said arm.

6. In a switch, a pair of contacts each provided with opposed contact surfaces, a contact arm having parts engageable with said opposed surfaces and means for separating said arm parts during the movement of said arm between contacts.

7. In a regulator switch, a plurality of contacts, each including a plate having opposed contact surfaces, a movable contact arm including parts resiliently urged into engagement with said opposed contact surfaces and means functioning during the transient movement of said arm between contacts for moving said contact arm parts out of their plane of contact.

8. In a switch, a pair of contacts, a contact arm having a portion engageable with said contacts, a member pivoted on said contact arm also engageable with said contacts and means for moving the contact engaging portion of the contact arm and the said member perpendicularly out of their planes of contact during transient movement of the contact arm.

9. In a switch, a pair of contacts, each provided with opposed surfaces, a contact arm having parts engageable with said opposed surfaces, means engageable with said contact arm for moving one of said parts perpendicularly out of its plane of contact and separate means engageable with one of the other of the said parts for moving the

same perpendicularly out of its plane of contact.

10. In a switch, a pair of contacts, a switch arm having a portion successively engageable with the upper faces of said contacts, and a member pivoted to the said switch arm respectively engageable with the under faces of the said contacts.

11. In a switch, a pair of contacts, a switch arm, a contact engaging member pivoted to said switch arm and a headed member extending through said switch arm and said pivoted member for urging the switch arm and pivoted member into engagement 10 with the said contacts.

15

12. In a switch, a plurality of contacts, and means successively engageable with said contacts, said means including a switch arm, a member pivoted to said switch arm, a spring having a portion bearing on the free 20 end of the switch arm, a headed member extending through the said pivoted member and the said spring, and resilient means sleeved on the said headed member and engaging the said spring, for urging the free 25 end of the contact arm and the pivoted contact engaging member into clamping engagement with the said contacts.

In testimony whereof I affix my signature.

HERBERT A. WOOFTER.
